UNITED STATES PATENT OFFICE.

VICTOR L. RONCI, OF BROOKLYN, NEW YORK, ASSIGNOR TO WESTERN ELECTRIC COMPANY, INCORPORATED, OF NEW YORK, N. Y., A CORPORATION OF NEW YORK.

ELECTRON-DISCHARGE DEVICE.

Application filed March 23, 1923. Serial No. 627,106.

To all whom it may concern:

Be it known that I, VICTOR L. RONCI, a citizen of the United States, residing at Brooklyn, in the county of Kings, State of New York, have invented certain new and useful Improvements in Electron-Discharge Devices, of which the following is a full, clear, concise, and exact description.

This application relates to electron discharge devices and pertains especially to the supporting of the electrodes.

The object of this invention is to attach securely metallic supporting rods and insulating members to provide a supporting structure for the electrodes.

To attain this object, the ends of the metallic supporting rods are threaded and passed through apertures in the insulating members and wire helices are screwed to the threads at opposite sides of the insulating members and in contact with the faces of said members to clamp them in position relative to the rods.

This arrangement makes possible the use of highly refractory metals such as molybdenum which could not be used in the form of nuts because of the difficulty of machining such metals. In addition, because of the use of highly refractory metals, the parts may be subjected to a higher heat treatment while being pre-glowed thereby shortening the time required for final pumping. The coils also require less space thereby providing a greater amount of insulation between the metallic supporting members and the other metal parts of the device.

Referring now to the drawings, Fig. 1 is an elevation, partially broken away, of an electron discharge device embodying the invention. Fig. 2 is a section on the line 2-2 of Fig. 1 and Fig. 3 is an enlarged detail view.

The invention is herein disclosed as embodied in an electron discharge device in which the anode 10 forms a portion of the containing vessel, a glass member 11 being sealed thereto from the stem of which (not shown) the electrode structure is supported by the metallic rods 12 in the well known manner. The ends of the rods 12 are threaded and extend through apertures in the insulating disc 13, this disc being a part of the electrode supporting structure. The arrangement of the ends of the members 12 within the apertures is such that the

threads extend on either side of the member 13. To maintain the member 13 in position relative to the rods 12, a wire helix 14 is arranged on the rod at either side of the member 13. These helices are preferably formed of a highly refractory metal wire such as molybdenum having a diameter approximately equal to the pitch of the threads on the rod and are tightly wound, the inner diameter of the coils being slightly less than the outside diameter of the threads. One of the helices is screwed on to the threaded end of the rod 12 before it is passed through the aperture in the member 13 and the other helix 14 is threaded on afterward. The two helices are screwed toward each other until they securely clamp between their adjacent ends the member 13'. The resiliency of the wire of which these helices are formed results in a lock-nut action between the various turns of the helices and prevents them from becoming loosened under ordinary conditions of use. This same method of attachment is used in connection with the rods 15, 16 and 17 which are shown extending from the member 13 into the envelope of the device.

The cylindrical form of the clamping members 14 serves to increase materially the insulation between the supporting rods over that when nuts of the ordinary type are used, and also renders uniform the space between the various adjacent rods.

The invention claimed is:

1. In an electron discharge device, an evacuated vessel, an insulating member having an aperture, a threaded metallic member extending through said aperture, and a helix of highly refractory metal having its turns engaging the threads on said metallic member, said helix having one end abutting said insulating member.

2. An electron discharge device comprising an evacuated vessel, an insulating member having an aperture, a threaded metallic member extending through said aperture, an abutment on said member, and a molybdenum wire wound in the threads of said member, one end of said wire being in contact with a face of said insulating member.

In witness whereof, I hereunto subscribe my name this 20 day of March A. D., 1923.

VICTOR L. RONCI.
